(57) **CLAIM**

The ornamental design for a rack, as shown and described.

DESCRIPTION

FIG. 1 is a perspective view of a rack showing my new design;

FIG. 2 is a front view thereof;

FIG. 3 is a rear view thereof;

FIG. 4 is a left view thereof;

FIG. 5 is a right view thereof;

FIG. 6 is a top view thereof;

FIG. 7 is a bottom view thereof;

FIG. 8 is a perspective view of the rack embodying different drawers;

FIG. 9 is a perspective view of the rack embodying different drawers; and,

FIG. 10 is a perspective view of a second embodiment.

The drawers shown in broken lines are for illustrative purposes only and form no part of the claimed design.
